PRESSING MACHINE ATTACHMENT

Samuel Blumenfeld, Detroit, Mich., assignor to
Clothing Devices, Inc., Detroit, Mich., a corpora-
tion of Michigan

Application September 1, 1945, Serial No. 614,029

5 Claims. (Cl. 223—39)

1

The present invention relates to a pressing machine attachment for use in forming and pressing trouser cuffs.

Difficulty is encountered in pressing trouser cuffs at the time they are made because, since the trouser leg is tapered, the turned up portion which forms the cuff is smaller than the overlapped portion of the trouser leg. Consequently, when the cuff is pressed for the first time, there is a tendency to wrinkle the trouser leg within and above the cuff. In addition, it has been necessary in the past to press the cuff while it was basted. As a result, the marks left by the basting threads had to be removed by a repressing operation.

It is one object of the present invention to provide an attachment for a conventional steam pressing machine capable of stretching and holding trouser cuffs in an extending flat position prior to and during the pressing operation, in order to prevent wrinkling of the trouser legs in and above the cuff.

Another object of the invention is to provide an attachment of the type mentioned which will permit removal of the basting threads prior to the initial pressing operation and thus obviate the necessity of repressing.

Another object of the invention is to provide an attachment of the type mentioned which may be readily mounted in position or removed from a conventional pressing machine without the use of any tools, in order to permit use of the machine for other purposes.

Another object of the invention is to provide an attachment of the type mentioned which will automatically accommodate cuffs of different sizes.

Other objects of the invention will become apparent from the following specification, accompanying drawings, and appended claims.

In the drawings:

Figure 1 is a side elevation of a conventional steam pressing machine showing the preferred form of the present invention mounted thereon;

Figure 2 is a fragmentary plan view of the attachment and the lower portion of the pressing machine taken on the line 2—2 of Figure 1;

Figure 3 is a fragmentary section taken on the line 3—3 of Figure 2.

Referring to the drawings there is illustrated, particularly in Figure 1, a conventional form of steam pressing machine which may be of any desired construction. The machine illustrated comprises a base 1 upon which is supported a stationary pressing buck 2. The machine includes a pressing head 3 which is pivotally connected by means of a pair of arms 4 to the base for swinging movement about the axis of a pipe 5, in the usual manner. A counter weight 6 is likewise mounted for pivotal motion about the

2

same axis and is connected to the head 3 by means of a tension rod 7. Since the details of construction of the pressing machine form no part of the present invention, they need not be further illustrated or described. It will be understood, however, that suitable means are provided to supply steam to the buck and head, and such means may include the previously mentioned pipe 5.

As best shown in Figures 2 and 3, the attachment of the present invention comprises a flat sheet-like member 8 which is formed of resilient material, such as sheet metal. Member 8 is secured at its rear edge to a transverse flat bar 9 and a pair of rearwardly extending flat bars 10 by means of rivets 11. The transverse bar 9 projects beyond the side edge of plate 8 and pivotally supports at its ends a pair of arms 12 by means of pins 13. The rearward ends of the arms 12 extend beyond the pivot pins and are connected by means of a spring 14 with the result that the forward ends of the arms are constantly urged outwardly toward the position illustrated in solid lines in Figure 2. The forward edge of the plate 8 is provided with a pair of forward projections 15 which extend approximately parallel to each other.

The rearwardly projecting bars 10 are each provided with a semi-circular upwardly curved section 16 adapted to rest upon the pipe 5. The bars 10 are connected by transverse bars 17 and 18. Transverse bar 17 is fixed to the bars 10 in any suitable manner as by means of rivets, while the transverse member 18 is adjustably connected to the bars 10 by means of stove bolts 19 which pass through slots 20 formed in the rear portion of the arms 10. As a result of this arrangement, the transverse member 19 may be shifted fore and aft on the bars 10.

The intermediate section of the transverse member 18 is curved downwardly as best shown in Figure 3 and is adapted to engage beneath the tension rod 7; and the adjustment of the transverse member 18 along the bars 10 is such that when the press is open, the plate 8 and arms 12 will be held in a position slightly elevated above the top surface of the buck 2 in the manner shown in Figure 3. It will be observed that no fastening devices are employed to secure the attachment in position and, consequently, it may be removed by simply lifting the forward end of the attachment until the bars 10 clear the pipe 5 and then moving the entire attachment to the left as viewed in Figure 3. The attachment may be installed by a reverse operation.

The operation of the device is as follows: With the parts in the positions illustrated in the drawings, the operator grasps one of the arms 12 and inserts that arm and the adjacent projection 15 into the basted cuff in the manner indicated in

60

dotted lines in Figure 2. As soon as one cuff is placed in position, the operation is repeated by inserting the other projection 15 and the other arm within the second cuff. The two trouser legs then assume the position indicated in dotted lines at 21 in Figure 2; and the tension of spring 14 stretches the material sufficiently to remove all wrinkles in the trouser leg and extend the cuff in a flat position slightly elevated above the buck. At that time, the operator may remove the basting threads without disturbing the form or condition of the cuff. Thereupon, the press is closed in the usual manner to press the cuff. During the downward swinging movement of the head 3, that portion of the tension rod 1 which overlies the transverse bar 18 will be elevated, permitting the plate 8 and arms 12 to lower 24 and contact with the buck. The arms 12 and plate 8, being formed of resilient material, may flex during the pressing operation to conform with the shape of the head and buck; and are sufficiently thin so that they will not interfere with the pressing operation.

It will be apparent that there is provided, in accordance with the present invention, an exceedingly simple and practical attachment, which may be readily installed on or removed from a conventional machine of any desired type. The attachment will automatically provide the proper degree of stretch for cuffs of various widths due to the action of spring 14. Since it holds the cuff and lower portion of the trouser leg in a stretched condition prior to the pressing operation, the cuffs may be inspected and the basting threads removed before closing the press and no wrinkles will be formed during the pressing operation. Consequently, the operation of forming and pressing trouser cuffs is greatly facilitated. The attachment may be instantly installed on or removed from the press at will with the result that the press may be used for other purposes without inconvenience.

The particular form of attaching means illustrated is specially adapted for use on a form of pressing machine which is widely used, but it is understood that the principles of the invention may be adapted for use on machines of differing construction without departing from the spirit of the invention. It is only necessary that the attaching bars include a portion which will rest upon a part of the head structure at one point and have a more rearwardly disposed portion which will engage beneath another portion of the head structure so that the attachment is supported in cantilever fashion above the buck and can be removed by simply lifting it out of contact.

What is claimed is:

1. A removable trouser cuff pressing attachment for the type of pressing machine which includes a stationary buck and a head structure pivoted to the buck on an axis located rearwardly of the buck, said attachment including a portion adapted to enter a trouser cuff and hold it in flat extended position adjacent the top surface of the buck and having an attaching portion extending rearwardly and adapted at one point to engage the upper surface of a portion of the head structure and at a more rearwardly located point being adapted to engage the under surface of a portion of the head structure to provide a cantilever support for the attachment which will hold the cuff engaging portion above the top surface of the buck, when the press is open.

2. A removable trouser cuff pressing attachment for the type of pressing machine which includes a stationary buck, a head pivoted to the buck on

an axis located rearwardly of the buck, a cylindrical member co-axial with said axis, and head counter-balancing means connected to the head and located rearwardly of said axis, said attachment comprising a member adapted to enter a trouser cuff and hold it in flat extended position adjacent the top surface of the buck and a rearwardly extending attaching portion secured to the member, said attaching portion having a recess in its lower side adapted to receive said cylindrical member and having a projection rearwardly of said recess adapted to project beneath and contact the under side of a portion of said counter-balancing means.

15 3. A removable trouser cuff pressing attachment for the type of pressing machine which includes a stationary buck, a head pivoted to the buck on an axis located rearwardly of the buck, a cylindrical member co-axial with said axis, and head counter-balancing means connected to the head, and located rearwardly of said axis, said attachment comprising a member adapted to enter a trouser cuff and hold it in flat extended position adjacent the top surface of the buck and a rearwardly extending attaching portion secured to the member, said attaching portion having a recess in its lower side adapted to receive said cylindrical member and having a projection rearwardly of said recess adapted to project beneath and contact the under side of a portion of said counter-balancing means, to hold the trouser cuff engaging member slightly above the top surface of the buck when the buck is elevated.

4. A trouser cuff pressing attachment for a steam pressing machine comprising a flat sheet of material having a pair of spaced projections extending in substantially the same direction and a pair of arms pivotally secured to the attachment and adapted to swing into positions in which their free ends lie substantially parallel to and on opposite sides of said projections respectively whereby the free end of one pivoted arm and one of said projections may be inserted in each trouser cuff, and resilient means for urging the free ends of the arms away from the projections to stretch the cuffs and hold them in a flat condition prior to pressing.

5. A trouser cuff pressing attachment for a steam pressing machine comprising a flat sheet of material having a pair of spaced projections extending in substantially the same direction and a pair of arms pivotally secured to the attachment and adapted to swing into positions in which their free ends lie substantially parallel to and on opposite sides of said projections respectively whereby the free end of one pivoted arm and one of said projections may be inserted in each trouser cuff, and resilient means for urging the free ends of the arms away from the projections to stretch the cuffs and hold them in a flat condition prior to pressing, and means for mounting the attachment on the pressing machine in slightly spaced relation but parallel to the pressing surface of the machine when the press is open.
